Inventor
J. L. Studds,

UNITED STATES PATENT OFFICE.

JULIAN L. STUDDS, OF ALEXANDRIA, VIRGINIA, ASSIGNOR OF ONE-HALF TO LEWIS E. SMOOT, OF WASHINGTON, DISTRICT OF COLUMBIA.

AUTOMATIC SAFETY GAGE-COCK.

1,000,455.

Specification of Letters Patent. Patented Aug. 15, 1911.

Application filed May 8, 1909. Serial No. 494,836.

To all whom it may concern:

Be it known that I, JULIAN L. STUDDS, a citizen of the United States, residing in Alexandria, in the county of Alexandria and 5 State of Virginia, have invented a new and useful Improvement in Automatic Safety Gage-Cocks, of which the following is a specification.

This invention relates generally to gage 10 cocks for locomotives, and steam boilers in general, and more particularly to a safety check valve to be used in connection with the gage cock for the purpose of preventing the escape of steam from the boiler in case the 15 gage cock valve is removed for any purpose, or in case the said gage cock should be broken off flush with the head of the boiler.

Another object of the invention is to provide a gage cock with a safety check valve, so 20 that the seat of the gage cock can be re-ground at any time desired, without letting down the steam pressure in the boiler, and a still further object is to provide for the intake of the water, and steam at the bottom 25 of the valve, instead of the end or top, and whereby clogging by scum or dirt is avoided, and it is also an object of this invention to provide a packing for the gage cock valve steam, so arranged as to prevent any grit 30 coming in contact with the threads of said stem.

With these and various other objects in view, my invention consists in the novel features of combination and construction, all 35 of which will be fully described hereinafter and pointed out in the claim.

In the drawing forming a part of this specification: Figure 1 is a side elevation showing the device in position for use, a 40 portion of the boiler head being shown in section. Fig. 2 is a longitudinal sectional view. Fig. 3 is a section on the line 3—3 of Fig. 2. Fig. 4 is a section on the line 4—4 of Fig. 2. Fig. 5 is a sectional elevation, 45 illustrating a modified construction.

In carrying out my invention, I employ a valve casing 1, which is provided with the usual central chamber 2, from which depends the discharge or drip pipe 3. The 50 inner end of this casing 1 is externally threaded, as shown at 4, for the purpose of screwing the casing into the end of the boiler, as shown at Fig. 1. This end of the casing is also threaded internally as shown 55 at 5, and is provided with a seat 6, in ad-

vance of the threads 5, and this seat 6 is intended to receive the cone-shaped check valve 7, for the purpose of cutting off the escape of steam or water from the boiler, and it will be noted that the valve seat and 60 check valve are arranged entirely within the boiler head, so that in case the gage cock casing should be broken off flush with the boiler, as is usually the case, the check valve 7 seating upon its valve-seat 6 would prevent the escape of steam or water from the 65 boiler.

A threaded plug 8, closed at its outer end is screwed into the inner end of the casing 1, this plug 8 having a central bore opening at 70 the forward end for the purpose of receiving the flattened guide stem 9 which carries the check valve 7. This plug 8 is constructed with openings 10, upon its under side, and which lead into the central bore, and through 75 which steam and water pass into the casing 1, and around the valve 7, when the said valve is opened or moved back from its seat.

The central chamber 2 has the usual pet 80 cock seat 2^a which is produced at the forward or outer end of the bore 11, which extends from the central chamber to the rear portion of the casing and through which steam and water pass, after passing the 85 valve 7. 13 indicates the pet cock valve stem having the tapered end 13^a, which seats against the seat 2^a for the purpose of cutting off the flow of steam or water. The forward portion of the stem is threaded, as shown at 90 14, and is provided with the usual construction of hand-wheel 15. The threaded portion of the stem works through a stuffing box 16, said stuffing box being screwed upon the threaded forward end of the casing, and 95 this stuffing box, it will be noted, is of different internal diameters, thereby providing an interior shoulder 16^a, against which a packing ring 17 rests, said packing ring being held between the shoulder 16^a and the 100 end of the pet cock casing, and by means of this construction the valve stem can be thoroughly packed, and all danger of grit, or any other substance reaching the stem is entirely avoided, and furthermore, the said 105 valve stem can be withdrawn, and inserted again, as often as desired, without repacking, or other inconvenience. The valve stem 13 with its tapered end 13^a will of course shut off the steam and water, wherever the 110

said valve is screwed in to seat firmly upon the seat 2^a, and whenever the engineer desires to test his boiler, he opens the valve, a sufficient distance, to unseat it. The check valve 7 heretofore referred to, is for the purpose of cutting off the escape of steam, and water in case the pet cock valve should be accidentally opened too far, or broken off entirely, but it will of course be understood that this check valve is to be unseated during the usual operations of the gage cock, and to accomplish this, I provide the check valve with a forwardly projecting stem 12 which is adapted to be engaged by the pin 12^a, screwed into the end of the gage cock valve 13^a, said stem and pin being of such relative length that a few turns of the handle will serve to open the gage cock, and at the same time keep the check valve open, but should the hand-wheel 15 be given an excessive number of turns, then the pin 12^a would be drawn out so far, as to permit the valve 7 to be seated, and thereby cut off the escape of either steam or water. This pin 12^a is screwed into the end of the valve 13^a and is made square in cross section, so as to be readily turned by means of a wrench or pliers.

In Fig. 5 I have shown a slight modification, in which the same number and relative arrangement of the various parts are used, but the casing 1 is made in two sections, 1^a and 1^b, the section 1^b carrying the safety check valve 7, and remaining in the boiler head at all times, while the section 1^a which is in reality a gage cock proper, can be quickly and easily removed therefrom, while the full steam pressure is on. It will be noted that these two sections are threaded together for the purpose of making one complete device.

The operations as before stated are identically the same.

By taking water and steam through the openings 10, from the under side of the plug, there is less danger of foreign matter working into the valve, than would be the case if the water were taken directly through an end opening.

It will thus be seen that I provide a gage cock with a safety check valve attachment, which will automatically operate to cut off the escape of steam, in case the gage cock casing is removed or broken off, and it will also be noted that the gage cock valve seat can be reground at any time with the full steam pressure in the boiler, and it will also be noted that the gage cock stem can be withdrawn and reinserted without repacking the stem, the packing remaining in place at all times.

Having thus fully described my invention, what I claim as new and desire to secure by Letters Patent is:—

In a gage cock, the combination with a casing threaded at its opposite ends, one end being threaded into the boiler, of a plug closed at its inner end, said plug being threaded into the inner end of the casing, said plug having an opening in its bottom thereof, a safety valve seated in the inner end of said casing, the seat for said valve being arranged within the head of boiler, a needle valve having a detachable pin adapted to engage the stem of the safety valve, said needle valve being adapted to be seated as the safety valve is opened and vice versa, said needle valve fitting snugly within the casing at the forward end, a stuffing box arranged upon said forward end and a packing held between said end and stuffing box, as set forth.

JULIAN L. STUDDS.
